UNITED STATES PATENT OFFICE.

CHARLES F. KETTERING AND WILLIAM A. CHRYSST, OF DAYTON, OHIO, ASSIGNEES TO
THE DAYTON ENGINEERING LABORATORIES COMPANY, A CORPORATION OF OHIO.

ELECTRICAL SYSTEM FOR ENGINES.

1,311,403.

Specification of Letters Patent. Patented July 29, 1919.

Application filed June 24, 1914, Serial No. 846,911. Renewed December 5, 1917. Serial No. 205,667.

To all whom it may concern:

Be it known that we, CHARLES F. KETTERING and WILLIAM A. CHRYSST, citizens of the United States of America, residing at Dayton, county of Montgomery, and State of Ohio, have invented certain new and useful Improvements in Electrical Systems for Engines, of which the following is a full, clear, and exact description.

10 This invention relates to improvements in electrical systems for internal combustion engines, and more particularly to improvements in that type of system in which electrical translation devices are interposed between the engine and a battery, for the purpose of charging the battery when driven by the engine, and to crank the engine when driven from the battery. As is well known, such systems may include the electrical ignition system for the engine, which may be supplied from the battery, which battery may also supply the lamps.

It is usual to employ in conjunction with systems of this character, a cut-out relay or 25 device for preventing flow of current from the battery into the generator, when the speed of the engine falls so low that the electromotive force generated by the electric machine does not overcome the battery 30 voltage, and it is among the objects of the present invention to provide a system of this character which will give satisfactory results in practice, without the use of a cut-out relay, such as is described above, and 35 without the attendant disadvantages which would otherwise exist, were no other measures taken to supply the place of the cut-out relay.

In accordance with the preferred embodiment of the invention which is hereinafter described, the generator circuit is directly connected with the battery through the intermediary of a manually controlled switch, and this switch is one which is ordinarily 40 employed in the operation of starting and stopping the engine, for example, the ignition switch. During the running of the engine, this switch is always retained in closed position, thereby maintaining the generator 45 circuit closed, and when the operator wishes to bring the car to rest, he opens the ignition 50 switch, thereby cutting off the ignition

and simultaneously opening the generator circuit.

In accordance with one feature of our invention, this control of the generator circuit through the ignition switch is combined with means for rendering the machine ineffective to drive the engine when the engine slows down or comes to rest with the said switch in closed position. In one preferred embodiment, we provide a suitable clutch, preferably a roller clutch, between the dynamo electric machine and the engine, so that if the operator should fail to stop the 55 car by shifting the ignition switch, for example, if the engine should "stall" under too heavy a load, then the dynamo electric machine will run freely as a motor without load, and as it will not be rigidly connected 60 with the engine, it will not be able to turn the engine shaft.

We have shown our invention herein applied to a dynamo electric machine starting device of the single unit type, that is to say, 75 a single dynamo electric machine which has both motor and generator functions, and the machine here illustrated is of the type provided with separate generator and motor field and armature windings, with provisions to connect the generator windings 80 with the battery for producing an initial movement of the machine to facilitate the enmeshment of the gears which connect it with the engine, the actual cranking operation being effected by connecting the motor 85 armature with the battery by means of a movable switch, which may be embodied in the form of a shiftable brush.

In applying the invention to a starting 90 device of this character, we may provide a switch movable into a position to establish a flow of current through the generator field and armature, which switch is preferably the ignition switch, and is provided with 95 means for maintaining it in this position until it is withdrawn from said position by the operator, for instance, when stopping the engine. For the purpose of cranking the engine, a second switch temporarily closes 100 the motor circuit, as is usual in systems of this character.

In the present embodiment of the invention, said first named switch establishes a

circuit through the generator field winding, which is maintained closed during the entire running of the engine.

In accordance with further features of the invention, we provide combinations of important improvements with various features of this type of starting apparatus, in such a manner as to produce the new and advantageous results more particularly hereinafter described.

Further objects and advantages of the present invention will appear from the description, reference being had to the accompanying drawings, wherein one preferred form of the present invention is clearly illustrated.

In the drawings:

Figure 1 is a diagrammatic view of the electrical circuits and connections which may be employed in connection with the present invention.

Fig. 2 is a fragmentary plan view of an automobile chassis, including an engine and illustrating certain parts of the present invention, as applied to said chassis and engine.

Fig. 3 is a rear end view of the dynamo-electric-machine with the end cover removed.

Fig. 4 is a view of the front end of the electric machine, with the inclosing covers or casings removed.

Fig. 5 is a top plan view of the electric machine shown in Fig. 4, the top casing thereof being removed for the sake of clearness.

Fig. 6 is a detail view of the front end casting of the electric machine.

Fig. 7 is a fragmentary view of the gearing between the starting device and the flywheel of the engine, which is brought into use for starting purposes. This view clearly shows the over-running clutch.

Fig. 8 is a fragmentary view of the front end clutch.

Fig. 9 is a view in elevation of the controlling switch unit.

Fig. 10 is a detail view of a part of the controlling switch unit, shown in Fig. 9.

Referring to the drawings and more particularly to Figs. 1 and 2, it will be noted that the present invention is illustrated as being installed on a motor vehicle, which may be of any approved type. The side frames of the vehicle chassis are indicated by the numerals 20, while the engine 21 is suitably supported therebetween, by means of the cross-supporting elements 22.

The dynamo-electric-machine 23 is preferably mounted adjacent to the engine, as is clearly shown in Fig. 2.

This electric machine is adapted to be connected with the engine and then operated as a motor for starting purposes. As soon as the engine becomes self actuating, the means for coupling the electric machine to the en-

gine for starting purposes, is disconnected and a different set of coupling mechanism connects the electric machine to the engine, whereby the machine is operated as a generator to store up power in a suitable accumulator for future starting operations, or to supply current for ignition, lighting or any other desirable purposes.

The means for coupling the dynamo-electric-machine 23 up to the engine, to operate the machine as a generator, comprises a shaft 24, one end of which is secured to the pinion 25, which meshes with the timing gear pinion 26. The opposite end of said shaft is connected to one of the co-operating elements of the friction clutch 29, which will now be described, and which is clearly shown in Fig. 8.

This clutch 29 comprises an external casing 30 having depressions 31 formed on the interior wall thereof at determined intervals. On the periphery of this external casing, a series of gear teeth are provided which engage with a pinion (not shown), which tends to drive the movable element of an associated ignition system.

In the present invention, the armature shaft 27 (see Fig. 8) is connected with a cam element 28, which fits within the exterior casing 30 above mentioned. This cam element is provided with a series of angular cut-away portions 32, wherein suitable friction gripping elements 33 preferably in the shape of rolls or balls are positioned.

The function and manner of operation of the above mentioned clutch as embodied in the present invention, will now be described.

When the electric machine is to be used as a motor for starting purposes, the armature 34 (see Figs. 3 and 4) is adapted to be connected to the engine through what might be termed a shiftable reduction gear in such a manner, that the speed of the armature shaft 27 will be much greater than that of the engine, and therefore of the shaft 24; therefore the armature must necessarily run ahead of the shaft 24, and one of the functions of this clutch is to permit it to operate in this manner.

The cam element 28 of the clutch 29 will therefore rotate relative to the external member 30 of said clutch, and the rolls 33 will consequently be moved over the depressions 31. As these rolls tend to pass the depressions 31, they will be displaced, with the result that as they come into contact with the depressed portion of the external element and are then forced back into normal position, a clicking noise will be created which of course will only take place at such times as the armature 34 of the generator is operating relative to and independently of the engine driven shaft 24.

The object of constructing the clutch in the above described manner, is to provide a

signal or indication that the armature is turning relative to the timing gears.

The advantage of this signal will appear more fully as the description of the operation and control of the system progresses.

The above mentioned clutch mechanism is positioned in the front end housing 35, which contains a plurality of compartments, as is clearly shown in Fig. 6. These compartments are shown, in the present figure, free from mechanism, but normally they are adapted to contain different units of mechanism, such as are clearly shown and described in our co-pending application, Serial No. 851,259, filed July 16, 1914.

The object and functions of the mechanisms contained in this casing, forms a part of the invention contained in said co-pending application, and therefore no detail illustration or description of these parts is deemed necessary in the present application.

The rear end of the armature shaft 27 is extended rearwardly beyond the end housing of the electric machine, as is clearly shown in Fig. 2, and carries a pinion 40.

The flywheel 41 of the combustion engine 21 is provided with a plurality of gear teeth 42, formed on or secured to the periphery thereof.

The armature pinion 40 is adapted to be connected with the flywheel gear teeth, by means of the shiftable reduction gear mechanism 43, which comprises a relatively large ring gear 44 and a small gear wheel or pinion 45. The large ring gear 44 in said reduction gear, being adapted to mesh with the armature pinion, while the relatively small gear wheel 45 is adapted to be brought into mesh with the flywheel gear teeth 42.

The mechanism for operating said shiftable gearing comprises a rod 46, connected to said gear by means of the yoke member 47, which is secured to said rod intermediate its two ends. The rear end of this rod 46 is connected to an operating pedal 48, while the extreme front end of said rod extends through the end casing 49 of the electric machine 23, and is adapted to operate relative to the commutator brushes of said machine in a manner described more fully hereinafter.

By referring to Fig. 7, the motor gear which comprises the reduction gearing 43, is shown as being provided with an internal clutch mechanism between the pinion 45 and the ring gear 44, which permits the engine, as soon as it has started, to operate under its own power, to carry the pinion 45 ahead of and relative to, the ring gear 44 and the armature pinion 40.

This clutch mechanism is substantially the same as that shown and described in the U. S. Patent No. 1,150,523, issued August 17, 1915, of Charles F. Kettering, and the application of Charles F. Kettering, Serial No.

721,237, filed September 19, 1912; and Charles F. Kettering and William A. Chryst, Serial No. 789,641, filed September 13, 1913; and therefore no further detail description of this structure will be given. 70

It has been stated heretofore, that the electric machine is adapted to be operated as a shunt-wound generator for charging purposes and as a compound-wound motor for starting purposes. The said machine is provided with independent shunt and series windings 50 and 51 respectively. 75

These windings are combined in a single coil 52, as is clearly shown in Figs. 3, 4 and 5, and are, of course, insulated from each other and properly taped or covered in any suitable manner. 80

Heretofore one great difficulty with machines of the present type, has been that of providing suitable connections between the field terminals and the other circuit connections. 85

This is especially true of windings which are constructed of relatively heavy strap or cable, as is the case in the present invention. 90

The series winding 51, preferably comprises a heavy metal strap having the desired number of turns to meet the conditions required. This strap is provided, as is shown in Fig. 5, with a terminal plate 56, 95 which is so connected to the strap that screw threaded lugs 57, constituting binding posts, project outwardly through a suitable casing 58 at the top of the generator. These lugs lie directly in position to be connected with the proper circuit connections. 100

The electric machine in the present instance, is what might be termed a two-purpose machine, and as has been explained heretofore, is provided with a plurality of 105 field windings which may be used independently or in determined combinations, to give the most advantageous results. The said machine also comprises a plurality of separate and independent armature windings 110 to be connected with the respective sets of field windings.

The armature 34 of the machine is therefore provided with a pair of commutators independently connected to the respective 115 armature windings of the machine. The generator commutator 60 is positioned at one end of the armature, as is shown in Fig. 4, and the motor commutator 61 is positioned at the opposite end of the armature, as is 120 shown in Fig. 3.

Referring particularly to Figs. 3, 4 and 5, it will be noted that the dynamo-electric machine comprises a pair of side frames 62, which are connected together by means of a 125 non-magnetic base 63, and a core 64 of magnetic material. This core provides a support for the field windings 50 and 51 respectively, mentioned heretofore.

The generator brushes, designated by the 130

numerals 65, are supported by means of a plate 66, the opposite ends of which are secured to the respective side frames 62. These brushes are at all times in engagement 5 with the commutator 60, and are so arranged and mounted upon the plate 66, that the springs 67 will maintain the said brushes in good electrical contact with the commutator 60.

10 The motor brushes clearly shown in Fig. 3, are mounted upon the brush-holder plate 68, which is of slightly different construction from that of the generator brush-holder 66. The plate 68 is provided with a 15 projecting finger, which in turn provides a support for the contact element 69, as is shown in Fig. 3, and which will be referred to more specifically hereinafter.

One of the motor brushes 70 is normally 20 in contact with the motor commutator 61, while the opposite brush 70 is normally maintained out of engagement with the motor commutator, by means of the rod 46 which has been referred to heretofore.

25 This rod is provided with a bevel end portion 71, so positioned that when the rod is drawn rearwardly by the operation of the pedal 48, the spring 70 will tend to force the brush 70 into engagement with the commutator and thus close the motor circuit.

The upper end of the brush arm 72, carries a contact plate 73 which is normally in engagement with the contact plate 69, and which normally tends to close the generator 35 armature circuit. It will be seen from Fig. 3, that when the commutator brush 70 is forced into position to contact with the commutator 61, the contact between the plates 69 and 73 will immediately be broken, thus 40 breaking the generator armature circuit for purposes to be explained more fully herein-after.

By referring to Fig. 1 of the drawings, 45 the electric machine 23, will be seen to comprise a generator armature winding 80. This armature winding as has been described heretofore, is connected with the commutator 60, which in turn is in contact with the brushes 65 at all times.

50 The generator circuit is initially controlled by means of either one of the controlling elements 82 or 83, of the switch unit 81.

By describing the circuits affected by the 55 operation of the elements 82 and 83 respectively, this will more clearly appear.

Supposing that the engine 21 is at rest, and it is desired to start the same, the following operations are necessary:—

60 First, the element 82 of the switch 81 will be pulled outwardly, providing magneto or generator type of ignition is to be used, and this operation will close the following ignition circuit: from the storage battery or ac- 65 cumulator 85, the current will flow through

the wire 86, wire 87, to the contact plate 88, across the conductive portion 89 of the pull-button element 82, through one side of the common contact element 90, through the wire 100, the primary winding of the induction coil 101, timing device 102, through the wire 103, to the point 104.

At this point the current will branch, a portion thereof going through the resistance 105 to the ground connection 106, back 75 to the other side of the battery which has the ground connection 107. The other portion of the current will flow through the wire 108, through the resistance 109 to the contact wiper 110, back to the battery via the 80 grounds 111 and 107.

The novel structure and arrangement of the resistances 105 and 109, in combination with the contact plate 110 have been clearly set forth in our co-pending application, 85 Serial No. 851,259, filed July 16, 1914, and therefore no detail description of these parts is deemed necessary.

At the same time the above mentioned circuit is completed, by the operation of the 90 pull-button element 82, the sliding plate 120 will be forced laterally, on the supporting plate or base 121, in such a manner as to close the contact plates 122 and 123 respectively.

95 The closing of these contacts will permit current to flow from the battery, through the wires 86 and 87, to the branch wire 124, through the contact plates 123 and 122 respectively, to the point 125, where the current will branch, a part thereof passing through one of the brushes 65, across the armature windings 80, the other brush 65, through the wire 126 to the contact plate 69, which as has been described heretofore, is 100 secured to the motor brush supporting plate 68. This plate 69 is normally in contact with the plate 73, and the current will therefore pass through these plates to the ground connection 127, back to the battery ground 110 connection 107.

105 The other portion of the current which divides at the point 125, will pass through the shunt field winding of the generator, through the wire 128, across the resistance 109, contact plate 110 to the ground connection 111, and back to the battery via the ground connection 107.

This will complete the generator circuit, and current will therefore flow as above 120 stated, and actuate the electric machine 23 as a motor, but it will of course be understood that the torque effect of the machine when operating under these conditions, will be much less than when the machine is operating under the influence of the regular motor windings.

125 As soon as the initial movement of the electric machine 23 takes place, the operator will depress the pedal 48, which will shift 130

the gearing 43 into position to couple up the electric machine 23 to the flywheel of the engine.

The operation of the pedal 48 will also 5 affect the closing of the motor circuit, and the concurrent breaking of the generator circuit by rocking the motor brush-holder 72, so as to bring the brush 70 into contact with the commutator 61, which movement will 10 separate the contact plates 69 and 73.

This operation of the pedal 48 breaks the generator armature circuit, by opening the contact plates 69 and 73, and it concurrently closes the motor starting circuit which is as 15 follows:

From the battery 85, current will flow through the wire 86, through the series winding 51, motor commutator brush 70, across the motor armature windings 140, 20 brush 70, to the ground 127, back to the battery via the battery ground 107.

Throughout this starting operation it will be noted that the field circuit of the generator has remained closed, and is used accumulatively with the series winding 51, thus increasing the torque effect of the motor, when used for cranking the engine.

As soon as the engine has become self-actuating, the operator releases the pedal 48, 30 which will return to its normal position, through the influence of the spring 141, which will of course also return the shiftable gearing 43, into such a position as to disconnect the engine from the electric machine 23.

Now, as soon as the engine speed becomes greater than a predetermined ratio of speed between the engine and the electric machine, the friction clutch illustrated in Fig. 8, will 40 be brought into effect to couple the electric machine to the engine, through the connections heretofore described, and thus drive the machine as a generator.

The release of the pedal 48, also permits 45 the spring 70^a to force the motor brush 70 out of contact with the commutator 61, and to bring the contact plates 73 and 69 together.

It will therefore be seen that the following circuit will be closed so long as the pull-button element 82 of the ignition system, is maintained in its outward position: from the generator armature windings 80, current will flow through the brush 65 to the point 55 125, where the field winding of the generator is cut in. Of course, a portion of the current will divert and pass through the generator field 50, and across the resistance 109, contact plate 110, ground 111 to the opposite brush of the generator, via the ground connection 127, contact arms 73 and 69 respectively.

The charging current will pass from the point 125 to the battery via the contact plates 122 and 123 respectively, through

wires 124, 87 and 86, and from the battery 85 back to the opposite side of the generator through the grounds 107 and 127, contact plates 73 and 69 respectively, and wire 126.

The manner of controlling the generator 70 output, and also controlling the ignition system, forms a part of our co-pending application, Serial No. 851,259, filed July 16, 1914, and therefore no description or showing of this means of regulation other than that disclosed in Fig. 1 will be made. 75

Exactly the same operation and functioning of the several units will take place, if the pull-button element 83 is operated instead of the element 82, with the exception 80 that the batteries 130 will form a source of the ignition current, so that the current will flow through the wire 131, contact plate 132, across the conductive portion 133 of the element 83, to the common contact plate 90, 85 from which point the circuits will be substantially the same as heretofore described, with reference to the circuits affected by the operation of the pull-button element 82.

In addition to the elements heretofore described as comprising the switch unit 81, a dimmer unit is carried by said switch and comprises a bobbin or spool 150, provided with a resistance coil 151, the opposite terminals of which are connected to the plates 90 152 and 153.

This dimmer is employed in conjunction with the head lights 174, shown diagrammatically in Fig. 1, and are so arranged that at such times as the lighting switch button 100 171 is in position shown in Fig. 1, it will be possible to close the headlight circuit through the dimmer resistance 151, by turning the button 170 to right angles, from the position shown in Fig. 1. 105

A circuit breaking interrupter 154 is also included in the lighting circuit, and is similar in operation to the circuit breaking interrupter described in the application of C. F. Kettering and W. A. Chryst, Serial No. 110 851,259, filed July 16, 1914. That is, this current interrupter is adapted to open and close the lighting circuit, as soon as an abnormal flow of current attempts to pass over the lighting circuit, thereby preventing the 115 burning out of the lamps and other associated work devices.

This circuit interrupter is constructed as a vibrating coil, in order that when the interrupter is in operation, quick making and 120 breaking of the lighting circuit will cause successive interruptions of the lights and thus the operator will be enabled to locate the cause of the abnormal flow of current immediately. 125

Under certain conditions it may be desirable to lock the ignition switch, and thereby not only prevent the operation of either of the ignition systems, but also to prevent the coupling up of the starting device to the 130

engine, by preventing the initial operation of the electric machine as a motor.

In Fig. 10 this locking mechanism is clearly shown as comprising a key-actuated button 175, having a locking cam 176, which when turned in the direction of the arrow 177, shown in Fig. 10, will bring the cam portion 176 into engagement with the plate 120, and thus maintain the plate in position 10 shown in Fig. 10, which will of course prevent the operation of either of the elements 82 or 83.

By the expression "direct circuit connections," employed in some of the claims which follow, we wish it to be understood that we mean direct circuit connections in the sense that they are not interrupted by the interposition of an electrical automatic cut-out relay or other automatic device, provided for the purpose of preventing the flow of current from the battery to the generator windings, when the battery voltage is greater than the generator voltage, as for example, when the engine stops.

25 While the form of mechanism herein shown and described constitutes a preferred form of embodiment of the invention, it is to be understood that other forms might be adopted, all coming within the scope of the 30 claims which follow.

The audible signaling device constituted by the clicking clutch element is claimed in our copending application Serial No. 79339, filed February 19th, 1916.

35 What we claim is as follows:

1. In a starting system for combustion engines, the combination with an engine; of a starting device comprising an electric machine, having motor and generator field and 40 armature windings, operable as a motor for starting purposes, and as a generator; an accumulator; circuit connections between said windings and the accumulator; an ignition system for said engine; means for bringing the ignition system into operation, and having provisions for closing the generator circuit; and an independent switch for bringing the machine into operation as a 45 motor for starting purposes, while the field circuit of the generator is closed.

2. In a starting system for combustion engines, the combination with an engine; of a starting device comprising an electric machine operable as a motor, and as a generator; an accumulator; motor and generator circuit connections; an ignition system for said engine; and means for bringing the ignition system into operation, and for closing the generator circuit; and an independent switch for bringing the machine into operation as a motor for starting purposes, by closing the motor circuit.

3. In an electrical system for engines, the combination with an engine; of an electric machine operable thereby as a generator; an

90 accumulator; circuit connections therebetween; an ignition system for said engine; and controlling means, comprising a plurality of operating members, each of which are operable to concurrently control the ignition system and the generator circuit connections.

4. In a starting device, the combination with a combustion engine, of an electric machine having a series and a shunt field winding, said machine being capable of operation either as a motor for starting said engine, or as a generator; an accumulator; circuit connections between said accumulator and the electric machine; an ignition system for said engine; means for bringing said ignition system into operation and concurrently closing the circuit connections between the electric machine and the accumulator, to impart an initial motor movement to said machine; and independent means for compounding the shunt and the series field winding for starting purposes, and for closing the motor circuit and breaking the generator charging circuit.

5. In a starting device, the combination with a combustion engine, of an electric machine having a series and a shunt field winding, said machine being capable of operation either as a motor for starting said engine, or as a generator; an accumulator; circuit connections between said accumulator and the electric machine; an ignition system for said engine; means for bringing said ignition system into operation and concurrently closing the circuit connections between the electric machine and the accumulator, to impart an initial motor movement to said machine; and independent means for compounding the shunt and the series field winding for starting purposes, and for closing the motor circuit and breaking the generator circuit, said means being operable to cut out the effect of the series winding, when the machine is to be used as a generator and reestablishing the generator charging circuit.

6. In a starting device, the combination with a combustion engine, of an electric machine having generator field and armature windings, and motor field and armature 115 windings, said machine being capable of operation as a generator for charging purposes, and as a motor for starting purposes; an accumulator; circuit connections between the electric machine and the accumulator; an ignition system for said combustion engine comprising a main circuit, a controlling member for closing said ignition circuit; means operated by said controlling element to close the generator field and armature circuits; and an independent switch for closing the motor circuit for starting purposes, and concurrently breaking the generator-armature circuit.

7. In an electrical system for combustion

engines, the combination with a combustion engine; of an electric machine operable as a motor for starting purposes, and as a generator for charging purposes; means for connecting the electric machine to the engine for starting purposes, said electric machine having an initial movement to facilitate the connecting of said engine to the electric machine; an accumulator; motor circuit connections and generator circuit connections between the electric machine and the accumulator; an ignition system; a controlling switch for said ignition system, comprising a controlling member operable to bring said ignition system into operation, and to concurrently close the generator field and armature circuit connections, to impart the above-mentioned initial motor movement to said machine, and to maintain said generator circuit connections closed throughout the operation of the electric machine as a generator.

8. In an electrical system for engines, the combination with an engine; of an electric machine operable thereby as a generator; an accumulator; circuit connections therebetween; a plurality of ignition systems for said engine; and a controlling switch comprising a plurality of manually operable members, each of which is operable to concurrently control one of said ignition systems and the generator circuit connections.

9. In an electrical system for engines, the combination with an engine; of an electric machine operable thereby as a generator; an accumulator; circuit connections therebetween including a set of contact elements; a plurality of ignition systems each including a set of contact plates; and a controlling switch including a plurality of operating members, each of which are operable to open and close the set of contacts in one of the ignition systems and the set of contacts in the generator circuit connections.

45 10. The combination with an engine, of a current-generating machine; a battery; a direct circuit connection between said current-generating machine and said battery through which the current generating machine charges the battery; an ignition system; a manually controlled switch, movable into open and closed positions to control the opening and closing of said direct circuit connection and concurrently controlling said ignition system; and means connecting said current-generating machine with the engine whereby the engine drives said machine to charge the battery with provisions for rendering said current-generating machine ineffective to drive the engine when the engine comes to rest with said switch in closed position.

11. The combination with an engine, of a current-generating machine; a battery; direct circuit connections between said cur-

rent-generating machine and said battery through which the current generating machine charges the battery; an ignition system; a manually controlled switch, movable into open and closed positions to control the opening and closing of said circuit connections and concurrently controlling said ignition system; and an automatic clutch interposed between said current generating machine and said engine.

75 12. The combination with an engine, a dynamo electric machine starting device therefor, including motor and generator windings; a battery; a direct circuit connection between the battery and the generator windings of the dynamo electric machine through which the dynamo electric machine charges the battery; a circuit connection between the battery and the motor windings of the dynamo electric machine; 80 a switch in said first named connection movable from an open position into a closed position, for connecting said generator windings with the battery to produce an initial operation of the starting device; means for 85 retaining said switch in closed position; a second switch arranged in said second mentioned connection and serving temporarily to connect the motor windings with the battery to cause the cranking of the engine.

90 13. The combination with an engine, of a dynamo electric machine starting device therefor, including a generator field and armature winding; a battery; direct circuit connections between said battery and dynamo electric machine through which the dynamo electric machine charges the battery; a switch in said connections movable into a position to establish a flow of battery current through said generator field and armature; 100 means for maintaining said switch in said position; and a second switch in said connections, adapted to break the circuit through the generator armature and establish the motor armature and field circuit.

110 14. The combination with an internal combustion engine, of a starting device therefor, including a dynamo electric machine comprising a generator armature and field and a motor armature and field; connecting gearing between said starting device and said engine, comprising high ratio motor gearing and low ratio generator gearing, said generator gearing including a clutch; a battery; direct electrical connections between said battery and said dynamo electric machine through which the dynamo electric machine charges the battery; a switch movable into a position to close said connections from the battery to the dynamo 120 electric machine through the generator field and armature; means for maintaining said switch in said position; and another switch movable to temporarily disconnect the generator armature from the battery and close 125

130

said connections between the battery and the motor armature and field circuit; and means for returning said switch into a position to reestablish the connection through the generator armature and break the connections to the motor circuit.

15. The combination with an engine, of a dynamo electric machine starting device therefor, including a generator field winding; a battery; direct circuit connections between said battery and dynamo electric machine; an ignition system; a switch in said connections movable into a position to establish a flow of battery current through 10 said generator field and armature, and to establish said ignition system in operation; means for maintaining said switch in closed position during the running of the engine; and a second switch in said connections, 15 adapted to break the circuit through the generator armature and establish the motor armature and field circuit.

16. The combination with an engine, of a dynamo electric machine starting device 20 therefor, including a generator field winding; a battery; direct circuit connections between said battery and dynamo electric machine through which the dynamo electric machine charges the battery; a switch in 25 said connections, movable into a position to establish a flow of battery current through said generator field and armature; means for maintaining said switch in said position during the running of the engine; a second 30 switch in said connections, adapted to break the circuit through the generator armature and establish the motor armature and field circuit for the engine cranking operation; and mechanical connections between the 35 dynamo electric machine and the engine, including a roller clutch through which the engine drives the dynamo electric machine.

17. The combination with an engine, of

electrical translation devices constituting a starting device for said engine, including 45 generator field and armature windings and motor field and armature windings; a battery; direct circuit connections between said battery and the electrical translation devices through which the generator field and armature winding are connected for charging the battery; a latched-in switch in said connections, movable into position to establish a flow of battery current through said generator field and armature windings to effect 50 an initial starting operation of the electrical translation devices; means for maintaining said switch in said circuit closing position during the running of the engine; and a manually controlled switch in said connections, adapted to temporarily establish the motor armature and field circuit for the engine cranking operation and to break said motor field and armature circuit after the starting operation has been accomplished. 55

18. In combination with an engine, a generator driven by said engine; a battery; direct circuit connections between the generator and battery through which the generator charges the battery; an engine-controlling member for controlling said engine and said direct circuit connections; and automatically operating means for preventing damage due to excess current passing into said generator when said engine comes 70 to rest with said direct circuit connections closed.

In testimony whereof we affix our signatures in the presence of two subscribing witnesses.
